US0D1032344S

(12) **United States Design Patent** (10) **Patent No.:** **US D1,032,344 S**
(45) **Date of Patent:** **** Jun. 25, 2024**

(54) **HOOKING DEVICE**

(71) Applicant: **Charles Weiss Sutliff, II**, Kila, MT
(US)

(72) Inventor: **Charles Weiss Sutliff, II**, Kila, MT
(US)

(**) Term: **15 Years**

(21) Appl. No.: **29/819,690**

(22) Filed: **Dec. 16, 2021**

Related U.S. Application Data

(62) Division of application No. 29/647,382, filed on May 11, 2018, now Pat. No. Des. 941,127.

(57) **CLAIM**

The ornamental design for a hooking device, as shown and described.

DESCRIPTION

FIG. 1 is a top perspective view of a new hooking device; FIG. 2 is a top view of FIG. 1, and the bottom view is the mirror image of the top view;

FIG. 3 is a first side view of FIG. 1;

FIG. 4 is a second side view of FIG. 1;

FIG. 5 is a first end view of FIG. 1;

FIG. 6 is a second end view of FIG. 1; and,

FIG. 7 is a demonstration of the hooking device in use with a rope.

The broken line showing a rope in the above FIG. 7 is for the purpose of showing environmental context and forms no part of the claimed design.

1 Claim, 2 Drawing Sheets
